US0D1054581S

(12) **United States Design Patent** (10) Patent No.: **US D1,054,581 S**
(45) Date of Patent: **** Dec. 17, 2024**

(54) **READER DEVICE**

(71) Applicant: **Erber AG**, Getzersdorf (AT)
(72) Inventors: **Evangelos Alexiadis**, Kent (GB);
Oliver Bishop, Alton (GB); **Andrew Spragg**, West Sussex (GB); **Ben Childs**, West Sussex (GB)

(73) Assignee: **Erber AG**, Getzersdorf (AT)

(**) Term: **15 Years**

(21) Appl. No.: **29/740,175**

(22) Filed: **Jul. 1, 2020**

(51) LOC (14) Cl. **24-02**
(52) U.S. Cl.
USPC **D24/216**

(57) **CLAIM**

The ornamental design for a reader device, as shown and described.

DESCRIPTION

FIG. 1 is a perspective view of a reader device;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines depict portions of the reader device that form no part of the claimed design.

1 Claim, 7 Drawing Sheets
